Filed Apr. 22, 1964, Ser. No. 79,658

Term of patent 14 years

(Cl. D13—1)

FIGURE 1 is a front perspective view of a shutter or similar article embodying my new design;

FIGURE 2 is an end elevational view of one end thereof;

FIGURE 3 is an end elevational view of the other end thereof;

FIGURE 4 is a front perspective view of a modified form of shutter or similar article embodying by new design; and

FIGURE 5 is an end elevational view of one end thereof, the other end thereof being substantially the same.

The rear portion of each shutter or similar article shown in FIGURES 1 through 5 of the drawings is substantially plain and unornamented.

The dominant features of my design reside in those portions shown in full lines in the drawings.

I claim:

The ornamental design for a shutter or similar article, substantially as shown and described.
